UNITED STATES PATENT OFFICE.

ALBERT THALHEIMER, OF READING, PENNSYLVANIA.

CIGAR-MAKERS' BOARD.

SPECIFICATION forming part of Letters Patent No. 291,644, dated January 8, 1884.

Application filed March 13, 1883. (No model.)

To all whom it may concern:

Be it known that I, ALBERT THALHEIMER, a citizen of the United States, residing at the city of Reading, county of Berks, State of Pennsylvania, have invented a new and useful Improvement in Cigar-Makers' Boards, of which the following is a specification.

This improvement relates more particularly to individual boards, usually carried from factory to factory by the owners thereof, but is applicable to all boards or tables for cigar-makers' use.

The object of the invention is to supply a light board for transportation, convertible into one of sufficient solidity when in use, and therewith to provide a cutting-face preservative of the edge of the hand-knife used for cutting the wrappers of the cigars. This I attain by making the top surface of the board or table of stamped metal, preferably of zinc, and filling out the back of the same flush with the flanges with a suitable plastic material.

Referring to the drawings, herewith forming a part of this specification, and in which similar letters refer to similar parts of the same, Figure 1 represents in perspective the application of my improvement. Fig. 2 represents an end elevation, partly in section, of the same, in which—

A represents a top for a cigar-maker's board, stamped in metal, A' being a plastic backing.

A² is a depression sunk in the face, in which the cigar is placed for trimming to size; A³, a scale which may also be stamped thereon or made visible in any other manner.

B represents the gage, secured in place by a thumb-screw, B'.

C represents a paste-cup, secured in a bracket, C'. If thought desirable, a depression for paste may be stamped at the same time as the top itself.

D represents a cigar-trimmer of the usual construction, adapted to be secured to the right-hand end of the board by screws D', the handle of the knife-lever being shown at E. Ears or lugs A⁴, at the opposite ends, serve to secure the device in place on the work-bench, screws being driven through the ears into the same, the ears A⁴ passed through the flanges, and embedded in the plastic backing, serve to bind the board A and its backing A' together while in use.

To apply the plastic backing A', the metal face A is laid upside down upon a level surface, and is then filled with fluid plaster-of-paris, cement, or a composition of glue and sawdust, papier-maché, or other equivalent material, which, soon hardening, forms a solid board.

When the operator desires to remove to another factory, he can easily displace the filling, and will have only the light metal top to carry away.

I have discovered practically that a zinc surface preserves the edge of the cigar-maker's hand-knife much longer than the wooden surface usually cut upon. This is owing to the fact that the wooden block, although set with the end of the block up, admits particles of sand and grit to embed themselves therein, which the zinc surface will not do, and is therefore always clean.

I do not confine myself to the form of board shown, as they may be stamped of an infinite variety of forms and depth.

The corners may be square or rounded on plan, as shown, and the top edge may be rounded also.

I make no claim to a cigar-maker's board *per se*, as they are old and well known to the trade; nor to the attachment of a cutter and paste-pot, as they are also common appliances; but I believe I am the first to use a stamped metal cover provided with a cigar-depression and the accessories thereto, and weighted by a filling of plastic material.

The drawing fully explains to an expert my improvement, and I desire to obtain Letters Patent for the following claim thereon:

I claim—

As a new article of manufacture, a stamped zinc metal facing for cigar-makers' boards, provided with the usual depressions and gage for the cigar, and, in combination therewith, a cigar-end cutter conveniently arranged thereon, said facing being filled out flush with the depth of the flanges with any suitable composition, whereby a surface preservative of the hand-knife edge is presented, and a light or heavy board produced, to adapt it to transportation or use, substantially as and for the purpose set forth.

ALBERT THALHEIMER,
